UNITED STATES PATENT OFFICE.

CHARLES E. SCHNEBELIN, OF PEORIA, ILLINOIS, ASSIGNOR TO STUBER & KUCK CO., OF PEORIA, ILLINOIS, A CORPORATION OF ILLINOIS.

CAN.

1,205,112.

Specification of Letters Patent. Patented Jan. 14, 1916.

Original application filed January 8, 1914, Serial No. 811,064. Divided and this application filed January 28, 1916. Serial No. 74,728.

To all whom it may concern:

Be it known that I, CHARLES E. SCHNEBELIN, citizen of the United States, residing at Peoria, in the county of Peoria and State of Illinois, have invented certain new and useful Improvements in Cans; and I do hereby declare that the following is a full, clear, and exact description of the invention, which will enable others skilled in the art to which it appertains to make and use the same:

This invention relates to improvements in cans particularly of the square or rectangular form and of that type for storing and shipping and in which to display various lines of goods.

As commonly constructed cans for shipping and for displaying goods are of rectangular or square form whereby openings may be made in one of the sides thereof through which the goods may be inspected. Some of this type, also, are constructed with an overhanging integral flange at the top edges of the walls with a view to strengthening the open top side but this, in practice, has not been found to be sufficient to prevent the cans being crushed under the strains imposed upon them requiring their return to the manufacturer to be straightened and repaired.

The object of my invention, therefore, in view of the above, is to provide a stiffening member for each of the corners of a can of this type which can be attached when thus returned for repairs, the article thereafter withstanding all ordinary hard usage without losing its proper form and neat appearance.

To the end that the invention may be fully understood I provide the accompanying drawing, in which,

Figure 1 shows, in perspective, the top portion of part of a rectangular form of can showing two of its angles or corners with my improved stiffening members attached at said angles or corners. Fig. 2 shows, in perspective, one of the stiffening members in an inverted position to clearly show its construction; and, Fig. 3 is a sectional elevation of a portion of the can and the stiffening member attached thereto.

The walls of the can are represented at A, and B represents an inwardly extending overhanging flange at the top edges of the

walls somewhat after the manner of cans of this type as sometimes constructed. The stiffening member comprised in my invention is represented as a whole in the several figures by the reference character C. It is preferably formed of one piece by means of suitable dies, for example, consisting of a top portion of two extensions lying at right angles to one another each overlying one of the flange portions B at the corner or angle, each said extension including a projecting lug E, as clearly illustrated in Fig. 2. In addition, each extension of the said stiffening member includes a flange portion F struck up at right angles, both of which in position on the can overlie the outer surfaces of the walls of the can as in Fig. 1, certain of said flanges being indicated by broken lines. After being placed upon the can the said lugs E are bent downward across the edge of the flange B and thence inward beneath it toward the adjacent wall of the can, Fig. 3, after which pressure clamps the lug upon the said flange B in a firm and substantial manner requiring no additional means of securing the member in place.

When constructed of a single part, or at least so that there is no joint at the meeting portions of the flanges F, it is clear that the member will be thoroughly rigid and no ordinary amount of rough usage or pressure cornerwise will bend the can out of shape even to the extent that its cover will be prevented properly fitting over it. The lugs E may of course cover as much of the flange as it may be the desire that it should, since it is not my purpose to be limited in any way to the exact form shown or to any particular dimensions, such changes being made as may fairly fall within the meaning of the invention and within the scope of the claims.

It is clear that the stiffening member may be attached to the upper edges of a can of any form whether or not said can is provided with the flange B such as shown.

This application is a divisional one of a copending application for a can, filed Jan. 8, 1914, under Serial No. 811,064.

Having thus described my invention, I claim:

1. The combination with a can two of whose walls lie at an angle to one another,

of a stiffening member at said angle of the walls comprising a portion overhanging a portion of the top edge of each wall at said angle, and a flange overlying part of the outer surface of each wall, each said portion of said member including a part folded upon and engaging the interior surface of the can and secured in place by the same.

2. The combination with a can, two of whose walls lie at an angle to one another forming an angle, one of the walls including a flange extending inward from its top edge at the open side of the can, of a stiffening member at the said angle including in its construction an extension overlying a portion of the flange measured lengthwise, said extension being folded upon and around the flange inside the can, and also including a part to engage the outer surface of the wall having the flange, said member being secured to the other wall of the can.

3. The combination with a receptacle whose walls lie at an angle to one another, terminating in an angle, each wall including an inwardly extending overhanging flange, of a stiffening member substantially conforming to the angle of said walls and lying upon the upper edges of the wall at said angle and upon each said flange, each extremity of the member including a part adapted to take around the flange, said member also including a flange on each of its extensions adapted to engage the outer surfaces of the walls at said corners.

4. The combination with a receptacle having an open side and having a corner formed by two of its meeting walls and including a flange at the top of each of the walls at said open side, of a stiffening member adapted for attachment to the receptacle at said corners comprising two extensions each adapted to overlie one of the said flanges at the top of the walls and including a flange adapted to overlie the outer surface of each wall, each said extension including a part at its inner edge adapted to be bent downwardly beneath and to clamp upon its respective flange of said walls.

5. An article of manufacture consisting of a sheet metal member having two extensions disposed in the same plane and lying at an angle to one another and each having a flange portion arranged perpendicularly thereto, each extension having an extending portion at its free extremity substantially at right angles to the length of said extension, the measurement of each said extremity across the extended portion being greater than the width of the extremity at other points in its length.

In testimony whereof I affix my signature in presence of two witnesses.

CHARLES F. SCHNEBELIN.
